COLLAR AND NECKTIE SUPPORT

Guy S. Christy, Medical Lake, Wash.

Application April 6, 1953, Serial No. 346,831

1 Claim. (Cl. 2-153)

1

This invention relates to a collar and necktie support and more particularly to a device for use in conjunction with four-in-hand ties and turn-down collars.

Various forms of combined collar and necktie supports have been previously devised and utilized but it has been found that these devices invariably lift the collar relative to the knot of the tie thus preventing the tie from achieving a proper drape and further enabling the tie to twist and turn resulting in an unsatisfactory appearance. It is therefore the primary object of this invention to provide a collar and necktie support which will substantially prevent the collar tabs from wrinkling while supporting the knot of a tie against twisting and in a substantially horizontal position so that the ends of the tie can readily achieve a highly effective and desirable drape.

Still further objects of the invention reside in the provision of a collar and necktie support that is strong and durable, simple in construction and manufacture, capable of being readily and easily utilized with various sizes of turn-down collars, capable of being constructed from various readily available materials and which is adapted to neatly and effectively hold a collar and necktie in its adjusted position even during comparatively strenuous movements of the user.

These, together with the various ancillary objects and features of the invention which will become apparent as the following description proceeds, are attained by this collar and necktie support, a preferred embodiment of which has been illustrated in the accompanying drawings, by way of example only, wherein:

Figure 1 is a front view illustrating the appearance of a necktie and collar supported by the device comprising the present invention;

Figure 2 is a side elevational view illustrating the necktie knot held in a substantially horizontal position and showing the device in dotted lines;

Figure 3 is a rear elevational view illustrating the manner in which a necktie is engaged with the end portions of this necktie and collar support;

Figure 4 is a perspective view of the device comprising the present invention; and,

Figure 5 is an enlarged sectional detail view as taken along the plane of line 5-5 in Figure 4.

With continuing reference to the accompanying drawings wherein like reference numerals designate similar parts throughout the various views, reference numeral 10 generally designates

2

a shirt having a collar 12 with tabs 14 and 16. The collar 12 is of the turn-down type and is adapted to be used in conjunction with four-in-hand ties 18. In order to support the tie so that it and the collar 12 will have the maximum attractiveness in their relationship the combined collar and necktie support generally designated at 20 and comprising the present invention has been provided.

10 The collar and necktie support 20 includes an arcuate central portion 22 having a central member 24 extending upwardly and outwardly therefrom. The central member 24 is formed from a pair of leg portions 26 and 28 integrally connected by a substantially horizontally extending arcuate central connecting portion 30. A clip 32 is positioned in embracing relationship about the legs 26 and 28 and has an end portion 34 wrapped about in embracing relationship with the arcuate central portion 22. This causes the central member 24 to be held in an adjusted position relative to the arcuate central portion 22.

At the ends of the arcuate central portion 22 are upwardly extending portions 36 and 38 which 25 terminate in inwardly extending portions 40 and 42. Substantially L-shaped collar supporting portions 44 and 46 are bent back from the inwardly extending portions 40 and 42 and terminate in hook portions 48 and 50. As can be 30 readily seen in Figure 3, the bight of the necktie extending about the collar of the individual utilizing this device is adapted to pass through the loops formed between the upwardly extending portions 36 and 38 and the L-shaped collar supporting portions 44 and 46. The inwardly extending portions 40 and 42 together with the substantially horizontal leg of the L-shaped portions 44 and 46 space the collar supporting L-shaped portions 44 and 46 from the rest of the shirt 10 35 to which the collar 12 is attached. Furthermore, the collar supporting portions 44 and 46 hold the collar tabs 14 and 16 in a preset desired position even though the individual wearing this device 20 were to subject himself to strenuous movement. The central member 24 holds the knot 52 of the tie 18 outwardly in a substantially horizontal plane to permit the ends of the tie to drape while also permitting the tie from 40 twisting.

45 Since from the foregoing, the construction and advantages of this necktie and collar support are readily apparent, further description is believed to be unnecessary.

However, since numerous modifications will 50 readily occur to those skilled in the art after a

consideration of the foregoing specification and accompanying drawings, it is not intended to limit the invention to the precise embodiment shown and described, but all suitable modifications and equivalents may be readily resorted to which fall within the scope of the appended claim.

What is claimed as new is as follows:

A collar and necktie support comprising an arcuate central portion having a central member extending upwardly and outwardly therefrom, said central member being adapted to support a necktie knot in a substantially horizontal position, said central member including a pair of leg portions integrally formed with said central member, said leg portions being joined by a connecting portion, a clip about said leg portions of said central member, said clip engaging said arcuate central portion to hold said central member in a predetermined desired angular relationship relative to said arcuate central portion, collar engaging means at the ends of said arcuate central portion for supporting the tabs of a collar and substantially preventing said collar from wrinkling, said collar engaging means including

upwardly extending portions terminating in inwardly extending portions, and substantially L-shaped collar supporting portions bent from said inwardly extending portions, said upwardly extending portions and said L-shaped collar supporting portions being adapted to receive a necktie therebetween, said inwardly extending portions spacing said L-shaped collar supporting portions from the rest of the shirt to which said collar is attached, said leg portions extending angularly upwardly and outwardly with respect to said arcuate central member and said L-shaped collar supporting portions.
